Primary Examiner — Mark Goodwin*(74) Attorney, Agent, or Firm* — Rashauna Norment(57) **CLAIM**

The ornamental design for a limb and branch trimming apparatus, as shown and described.

DESCRIPTION

FIG. 1 is a perspective view of a limb and branch trimming apparatus, showing my new design;

FIG. 2 is a top plan view of FIG. 1 thereof;

FIG. 3 is a bottom plan view of FIG. 1 thereof;

FIG. 4 is a front plan elevation view of FIG. 1 thereof;

FIG. 5 is a rear plan elevation view of FIG. 1 thereof;

FIG. 6 is a left side elevation view of FIG. 1 thereof;

FIG. 7 is a right side elevation view of FIG. 1 thereof;

FIG. 8 is another perspective view of FIG. 1 thereof, showing an exploded view of the invention;

FIG. 9 is a top plan view of FIG. 8 thereof;

FIG. 10 is a bottom plan view of FIG. 8 thereof;

FIG. 11 is a front plan elevation view of FIG. 8 thereof;

FIG. 12 is a rear plan elevation view of FIG. 8 thereof;

FIG. 13 is a left side elevation view of FIG. 8 thereof; and,

FIG. 14 is a right side elevation view of FIG. 8 thereof.

The broken lines showing an engine depict environmental subject matter and form no part of the claimed design.

1 Claim, 12 Drawing Sheets(56)
